UNITED STATES PATENT OFFICE.

RUFUS C. BASSETT, OF COMANCHE, TEXAS.

KNEE-PROTECTOR.

1,131,816.

Specification of Letters Patent. Patented Mar. 16, 1915.

Application filed June 9, 1914. Serial No. 844,048.

To all whom it may concern:

Be it known that I, RUFUS C. BASSETT, a citizen of the United States, residing at Comanche, in the county of Comanche and State of Texas, have invented a new and useful Knee-Protector, of which the following is a specification.

The present invention appertains to knee protectors, and aims to provide a novel and improved knee protector adapted to be worn by cotton pickers, miners, and other workers who are required to walk or labor while resting on the knees.

The present invention contemplates the provision of a knee protector of unique construction, whereby it will be peculiarly adapted for the intended purposes, the present device while applied to the knee, permitting the wearer to walk conveniently either while standing or kneeling.

Another object of the invention is to provide a knee protector which will conveniently and effectively accommodate the knee of the wearer and which will permit the leg to be straightened out without difficulty when the wearer assumes a standing position.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:—

Figure 1 is a side elevation of the improved knee protector as in use. Fig. 2 is an enlarged plan view of the device. Fig. 3 is a vertical section taken on the line 3—3 of Fig. 2.

The frame of the present invention includes a pair of upright strips or bars 1 which have their lower ends bent angularly inward, as at 2, and riveted or otherwise secured upon the end portions of a semi-circular or arcuate base plate or foot 3. The arcuate base plate or foot 3 projects forwardly from the side bars 1, and the bars 1 are connected above the foot 3 by forwardly curved yokes 4 which are arranged to surround the forward portion of the limb

above the knee when the frame is set astride the limb over the knee joint. The forward portion of the foot plate 3 is curved upward slightly.

In order to hold the frame in place upon the limb, a pair of straps 5 are attached to one of the side bars 1 in rear of the yokes 4, and buckles 6 are attached to the other bar 1 opposite the basal ends of the straps 5. The lower strap 5 is arranged to pass in rear of the knee joint, while the upper strap 5 is arranged to pass in rear of the thigh above the knee, and the free ends of the straps 5 are adjustably engageable with the buckles 6 to thereby cause the yokes 4 and straps 5 to snugly embrace the limb directly above the knee joint.

Yieldably mounted between the side bars 1 is a knee pad or stirrup 7, which incorporates a pair of side members 8 having their central or intermediate portions pivoted upon the inner ends of the bolts 9 slidably within longitudinal or vertical slots 10 formed in the bars 1 adjacent their lower ends. An endless pad or stirrup element 11 is passed around the side members 8 and is provided with the openings 12 intermediate its edges through which the bolts or pivot members 9 are passed, it being observed that the pad or saddle 7, including the members 8 and the fabric or textile element 11, may swing forward and rearwardly about a transverse horizontal axis.

As a means for yieldingly supporting the pad or stirrup 7, inner and outer washers 13 are mounted upon the bolts 9 adjacent the inner and outer sides of the bars 1, and the outer washers 14 are provided with upper hooks 15, while the bars 1 are provided above the hooks 15, with complementary hooks 16. Coiled wire retractile springs 17 are disposed upon the outer sides of the bars 1 and have their ends engaged to the respective hooks 15 and 16, to thereby yieldably support the bolts or pivot members 9.

In applying the protector to the limb, the frame of the protector is placed astride the limb adjacent the knee, so that the yokes 4 surround the forward portion of the thigh directly above the knee joint. The straps 5 are then passed around the back of the knee joint and thigh and are attached to the buckles 6, whereby the yokes 4 and straps 5 will girdle the lower portion of the thigh directly above the knee joint. The lower strap 5 fitting snugly in rear of the

knee joint will permit the limb to be readily doubled or straightened out, and at the same time, the two straps 5 will effectively hold the yokes 4 snugly against the limb.

5 The knee is adapted to rest upon the textile or fabric element 11, which will provide a comparatively soft or yielding pad element for the knee, and when the weight of the wearer is imposed upon the knee, the 10 pad or stirrup 7 may yield inasmuch as the pivot members 9 may be depressed within the slots 10 and are yieldably supported by the springs 17. In this manner, the pad or stirrup is not only inherently yieldable, 15 but is yieldably supported, to render the protector comfortable in its use, and to avoid chafing or other injury to the knee. Another advantage resides in the fact that the pad or stirrup is pivotally mounted between the bars 1, whereby the pad or stirrup 20 may swing to properly accommodate the knee, and furthermore, when the limb is straightened out, the pad or stirrup 11 may swing to an approximately vertical position, so that the wearer may walk while 25 in an erected position. To this end, it is also to be observed that the base plate or foot piece 3 being curved forwardly, will enable the same to receive or accommodate 30 the limb below the knee joint while the wearer is walking.

It is of course understood, that the present device is worn in pairs, in order that the wearer may walk or labor upon his knees, 35 and when doing so, the pads or stirrup upon which the knees rest, are spaced above the soil or underlying surface, to prevent the knees from contacting with the hard soil, hot sand, rocks, mud and the like. As the 40 wearer walks upon the knees, the pad 11 will swing or oscillate properly, according to the movement of the respective limb, and furthermore, each pad will yield under the varying conditions, to the comfort of the 45 wearer.

The arcuate base plate or foot 3 provides a relatively large bearing surface, in order that the protector may rest flatly or effectively upon the soil or other surface, and 50 whereby the protector will not be liable to sink readily into soft or muddy soil, sand and the like. The peculiar foot piece 3 also enables the wearer to conveniently and readily walk while on his knees.

55 The present device is particularly adapted for protecting the knee while walking or laboring thereon and for preventing the

knee from engaging the soil, or the like, as not infrequently results in chafing, rheumatism, and other ailments. The inner 60 sides of the side bars 1 are smooth and unencumbered, to prevent injury to the limb while the limb reciprocates slightly within the frame, due to the yielding movement of the pad or stirrup 7, and the present device is of advantage in other respects as will be apparent from the foregoing, taken in connection with the drawing.

Having thus described the invention, what is claimed as new is:—

1. A knee protector including side bars having slots therein, members working within the slots, springs disposed upon the outer sides of the said bars and yieldably supporting the said members, and a knee 75 pad carried by the said members between the said bars.

2. A knee protector including side bars having slots, pivot members working within the said slots, springs disposed upon 80 the outer sides of the bars and connected to the said pivot members to yieldably support the same, and a knee pad disposed between the said bars and including side members pivotally engaged with the said pivot members and a yieldable element connecting the said side members.

3. A knee protector embodying side bars having forwardly projecting yokes connecting them, a forwardly projecting arcuate 90 foot piece attached to the lower ends of the side bars and arranged to let the leg be straightened out, a yieldable knee pad mounted between the said bars, and straps for connecting the side bars adapted to co- 95 operate with the said yokes to girdle a limb above the knee joint.

4. A knee protector embodying side bars having forwardly projecting yokes connecting them, a forwardly projecting arcuate 100 foot piece attached to the lower ends of the side bars and arranged to let the leg be straightened out, a knee pad pivotally and yieldably mounted between the side bars, and straps for connecting the side bars 105 adapted to co-operate with the said yokes to girdle a limb above the knee joint.

In testimony that I claim the foregoing as my own, I have hereto affixed my signature in the presence of two witnesses.

RUFUS C. BASSETT.
